United States Patent Office

Des. 185,345
Patented June 2, 1959

185,345

BUCKLE

Harold F. Burnham, Highland Park, N.J., assignor to Personal Products Corporation, a corporation of New Jersey

Application November 20, 1958, Serial No. 53,453

Term of patent 14 years

(Cl. D17—1)

Fig. 1 is a plan view of a buckle showing my new design; and

Fig. 2 is a side edge view.

I claim:

The ornamental design for a buckle, as shown.
